UNITED STATES PATENT OFFICE.

FRANK L. LINDSTROM, OF BRIDGEPORT, CONNECTICUT.

TOY.

Application filed January 21, 1922. Serial No. 530,779.

To all whom it may concern:

Be it known that FRANK L. LINDSTROM, a citizen of the United States, and resident of Bridgeport, in the county of Fairfield 5 and State of Connecticut, has invented certain new and useful Improvements in Toys, of which the following is a specification.

This invention relates to a new and improved toy of that type which can be made 10 to move apparently automatically, with motions resembling those of live creatures.

The object of the invention is to provide a toy of the present character which will be extremely simple in construction and 15 quite cheap to manufacture, and which will at the same time be of a practical, durable structure not liable to become impaired, whereby the toy may be capable of functioning for a long period.

20 With the above and other objects in view, the invention resides and consists in the novel construction, arrangement, and combination of parts now to be fully described and later to be specifically claimed; it being understood that slight changes in details of construction and arrangement of parts may be made without departing from the spirit of the invention and the scope 25 of the appended claims.

30 In the accompanying drawing forming a part of this specification,

Fig. 1 is a vertical sectional view of a toy embodying the features of the invention;

Fig. 2 is a central sectional view on an 35 enlarged scale of the differential winding drum of the toy as seen in Fig. 1; and

Figs. 3, 4, 5, 6 and 7 are each, respectively, a plan and a sectional view of the several parts of the differential winding 40 drum.

The toy of the present invention, as very clearly shown, includes a differential winding drum having cords attached thereto and so arranged that by pulling upon one cord 45 the toy will be made to move along the other cord, or by slackening the cords will return to its former position. That is, by grasping and holding one cord and pulling on the other cord, one cord will be wound 50 upon the drum and the other will be unwound, the difference in diameter of the two parts of the drum causing the toy to progress along one of the cords. To obtain best results the cords are held approximately 55 in vertical position, one being pulled up and

the other down. By pulling on the cords the figure moves upwardly and by slackening the cords gravity will cause the figure to go down again. The present toy also includes, as is usual in the case of toys of 60 the present type, means for operating the legs and arms of the toy as it moves up and down, so as to give the appearance that the legs and arms of the creature were moving, carrying the body. 65

Specifically, it is the aim of this invention to provide a novel and simple construction of differential winding drum which can be formed of a lesser number of 70 parts than those now upon the market and thereby constructed at small expense, whereby the market price of toys of the present nature will be considerably reduced and a fair profit yet derived; and to provide simple and improved means for moving the 75 legs and arms of the toy up and down as the drum is rotating.

Referring to the drawing 10 denotes the body of the toy which may be made to represent the body of an animal, fish, bird 80 or the like. As shown, it represents a monkey having a head 11 and a tail 12. Numeral 13 represents a jacket which may be secured upon the body in any preferred manner as by means of bent over lugs 14 85 and 15.

Within the body and jacket is an enclosed housing for a differential winding drum, through which the toy is operated. This 90 housing is formed of two sheet metal stampings in the form of a cup 16 and cover 17, both of which include an annular flange portion, the flange of the cover being narrower than the cup and adapted to fit on the wider flange of the cup forming the 95 main cylindrical body portion of the housing. A central depression 18 is formed in both the cup and cover, forming bearings for drum shaft 19 that extends through 100 holes in said depression. The ends of this shaft are supported in sockets of the opposite sides of the body 10, and an enlargement 20 arranged intermediate the ends of the shaft is for the purpose of forming a 105 shoulder to hold the drum against endwise movement. This housing is constructed of a suitable grade of sheet metal and together with the enclosed winding drum forms a unit that can be secured in the body in any manner as by means of lugs 21 struck from the 110

base and cover and turned over and clamped against the edges of the body at the opposite sides. See Fig. 1.

The differential winding drum, like the housing, is constructed of the least possible number of parts, seven including the shaft, and is mounted to rotate upon the shaft 19 journaled in the before mentioned bearings in 18. This winding drum comprises a small pulley 22 and a large pulley 23 both secured together to turn as one. Each pulley is formed of three sheet metal stampings suitably shaped and secured together to form a rotatable unit.

15 The smaller cylindrical portion of the differential winding drum may be best described as the small pulley and the larger cylindrical portion as the larger pulley. The small pulley 22 is made up of a drawn cup like sheet 24 which includes an annular cylindrical portion 25 and a base 26 having holes 27 therein to receive struck up lugs 28 of and for the attachment of a flat plate 29 that forms one of the annular flanges of 25 the pulley. The annular edge portion of the small shell 24 includes a series of lugs 30 that extend through the holes 31 in the outer closure plate 32 that forms the outer flange of the small pulley. This plate is 30 preferably provided with a central stamped up bearing portion 33 in which a hole is formed to receive the shaft 19.

The before mentioned flat plate 29, see Fig. 5, is further provided with a series of 35 three shouldered lugs 34 which are disposed out at right angles, on the opposite side of the plate from lugs 28, and serve the double purpose of forming an eccentric bearing and for connecting the two pulleys 40 together in spaced relation to each other. The shoulders of these lugs 34 obviously set up against the side of the adjacent flange plate 35 of the large pulley while the smaller end portions of the lugs are 45 positioned in the holes 36 of the plate and holes 37 of the larger cup shaped member 38. This larger cup includes a bottom portion 39, a cylindrical pulley face 40 and an annular pulley flange 41 projected from 50 the outer edge of the pulley to conform with the flange of the plate 35. This plate 35 is provided with a single lug 60 that is for the purpose of engaging the hole 61 of the large pulley cup for further securing 55 the two parts together. The outer side of the large cup 38 is enclosed by a shaped disk 42 which includes an annular flange 43 that fits into the cup and further includes a stamped up central portion 44 having a 60 hole therethrough and forming a bearing on the shaft.

The two pulleys are thus secured together to turn as one upon its shaft though are spaced apart by reason of the shouldered 65 construction of the lugs 34 to provide room

for the eccentric links 45 and 46 mounted upon said lugs which form a bearing for the ring portion of the links. Both of the pulleys are provided with flanges upon each side to better support the operating cords 70 47 and 48 wound thereon.

The three lugs 34 connecting the pulleys are located at different and suitable distances from the shaft 19 to serve as an eccentric for links 45 and 46 having pivotal connection as at 49 and 50 with the rockable crank-shafts 51 and 52 for operating the legs and arms 53 and 54 respectively. Numeral 55 denotes pivots between the upper and lower parts of the legs and arms, 80 respectively. The cord 48 is attached to the large pulley and extends out through slot 56 in the housing and through holes 57 in the extremities of the arms. Cord 47 attached to the smaller pulley extends 85 through a slot 58 in the housing and through holes 59 in the feet and tail so as to guide the movement of the toy along the line of the cord. Each of the links 45 and 46 has a ring encircling the lugs 34 90 and the bodies of said links are freely slideable in the slots 62 of the housing, whereby when the drum is rotated in the housing and on the shaft 19 the links will cause the crank shafts to oscillate and swing the 95 legs and arms thus producing movements of said legs and arms, guided by the cords, resembling those of live creatures.

Having thus fully described the invention, what I claim as new and desire to 100 secure by Letters Patent is:

1. A toy of the character described, comprising a body and a differential winding drum mounted therein, said winding drum consisting of a pair of pulleys connected to 105 turn with each other, and one of said pulleys consisting of a plurality of stampings including a cup shaped member having an annular pulley face and an integral bottom having a central perforation forming a 110 bearing for the pulley, and a flange plate secured at the open side of said cup shaped member and having a central perforation forming a second bearing for the pulley spaced from said first bearing, and a shaft 115 supported by said body and engaging said bearings.

2. A toy of the character described, comprising a body, arm and leg members pivotally connected to the body and having cranks, a differential winding drum mounted to turn in the body, said drum consisting of a pair of spaced apart sheet metal pulleys, a plurality of lugs struck from the side of one of the pulleys and connected to 120 the side of the other pulley, to space and connect them to turn one with the other, said lugs being arranged in an eccentric circle about the axis of the pulleys to form a bearing, and a member comprising a ring por- 130

tion engaging said bearing, and arm portions extended to connect with said cranks of said arms and legs to oscillate them.

3. A toy of the character described comprising a body having spaced apart sockets, a shaft having its opposite ends arranged in said sockets, an enlargement on said shaft and spaced from said body, a cylindrical housing having a peripheral and side portions, said side portions having central apertured depressions pressed inwardly toward each other, said housing mounted on said shaft, a differential winding drum within said housing and including a pair of pulleys mounted at opposite sides of said enlargement, said differential winding drum having oppositely disposed protuberances engaging the depressions of the housing, whereby thrust bearings are provided for said differential winding drum.

4. A toy of the character described comprising a body having spaced apart sockets, a shaft the opposite ends of which are secured in said sockets, an enlargement on said shaft and spaced from said sockets, a housing upon said shaft and including a cup and a cover each having depressions, a differential winding drum upon said shaft and including a pair of pulleys arranged at

opposite sides of said enlargement and between said depressions, one of said pulleys consisting of a disc having a protuberance engaging the material adjacent one of said depressions, a cup member inclosing said shaped disc, and a flat plate secured to said cup and the other of said pulleys consisting of a flat plate having a protuberance engaging the material adjacent the other of said depressions, a small cup having extensions secured to the flat plate, and a flat disc having lugs secured to the cup and also having lugs secured to the flat disc of the first mentioned pulley.

5. A toy as specified in claim 4, wherein the lugs securing the pulleys to each other are arranged at different distances from the shaft, and links having rings and enveloping said lugs are provided and are pivotally connected with legs and arms, respectively, upon said toy for the purpose specified.

Signed at Bridgeport in the county of Fairfield and State of Connecticut this 19th day of January, A. D., 1922.
